(57) **CLAIM**

The ornamental design for a residual pressure release valve, as shown and described.

DESCRIPTION

FIG. 1 is a front, top and left side perspective view of a residual pressure release valve showing our new design; FIG. 2 is a rear, bottom and right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof; and,

FIG. 8 is a right side view thereof.

The broken lines depict portions of the residual pressure release valve that form no part of the claimed design.
